(57) **CLAIM**

The ornamental design for a roof of a recreational vehicle, as shown and described.

DESCRIPTION

1. Roof of a recreational vehicle
  - 1.1 is a rear elevation view of a roof of a recreational vehicle embodying my new design;
  - 1.2 is a front elevation view thereof;
  - 1.3 is a top, front, and right side perspective view thereof;
  - 1.4 is a right side elevation view thereof;
  - 1.5 is a top plan view thereof;
  - 1.6 is a rear elevation view thereof in a collapsed state;
  - 1.7 is a front elevation view thereof in a collapsed state;
  - 1.8 is a top, front, and right side elevation view thereof in a collapsed state;
  - 1.9 is a right side elevation view thereof in a collapsed state; and
  - 1.10 is a top plan view thereof in a collapsed state.
- Pop-up roof for recreational vehicles.
